STEAM GUN AND BRUSH COMBINATION

Charles D. Clobridge, Monroe, Mich.

Application September 27, 1943, Serial No. 504,011

3 Claims. (Cl. 68—222)

This invention relates generally to cleaning equipment and refers more particularly to a steam gun and brush combination.

One of the essential objects of the invention is to provide a combination of this type wherein the brush may be quickly attached to or detached from the steam gun.

Another object is to provide a combination wherein the attaching means includes means for yieldably maintaining and holding the brush in an operative position relative to the steam gun.

Another object is to provide a combination that obviates special couplings or connecting means such as screw threads, clamps and other fasteners that not only are expensive to make and assemble with the respective parts of the combination, but lack the yieldable feature aforesaid.

Another object is to provide a combination wherein brushes of various sizes, types and styles may be interchanged upon the steam gun or equivalent fluid supplying device.

Another object is to provide a combination wherein the brushes may be readily connected by the attaching means mentioned to substantially L-shaped heads of fluid supplying devices other than steam guns for enabling fluids other than steam to be supplied to the bristles or other rubbing or scrubbing elements of the brushes.

Another object is to provide a combination that accomplishes the results desired with a minimum of parts.

Another object is to provide a combination that is capable of being readily cleansed.

Another object is to provide a combination wherein the separable connection between the parts is such that either of said parts may be used alone whenever desired.

Another object is to provide a combination that is simple in construction, economical to manufacture, and efficient in operation.

Other objects, advantages and novel details of construction of this invention will be made more apparent as this description proceeds, especially when considered in connection with the accompanying drawing, wherein:

Figure 1 is a perspective view of a steam gun and brush combination embodying my invention;

Figure 2 is a fragmentary longitudinal sectional view through the combination;

Figure 3 is a fragmentary cross sectional view through the combination;

Figure 4 is a view similar to Figure 2 but showing a slight modification;

Figure 5 is a top plan view of the structure illustrated in Figure 4.

Referring to the drawing, A is the steam gun, B is the brush, and C is the means by which the brush is attached to the gun.

As shown, the steam gun A has a handle 10 containing the shank 11 of an inverted substantially L-shaped nozzle 12. Steam or other fluid from a suitable source (not shown) may flow through connecting passages 13 and 14, respectively, in the shank 11 and nozzle 12 to a restricted outlet 15 and may be under the control of one or more valves (not shown).

The brush B has a head 20 provided at approximately the center thereof with an oblong opening 21 for the outlet end portion 22 of the nozzle, and is provided on the underside of said head about the opening 21 with bristles 23 for engagement with the article or object (not shown) to be cleaned. Thus, the bristles 23 are spaced apart to provide a passageway 24 for steam or other fluid from the outlet 15 of the nozzle.

The attaching means C is flexible, yieldable and elastic and preferably comprises two coil springs 30 and 31 terminally connected to opposite side edges of the brush head 20 at longitudinally spaced points thereof and forming upstanding substantially parallel inverted U-shaped loops 30 for straddling the shank 11 of the nozzle. Preferably this construction and arrangement of parts is such that the springs 30 and 31 incline toward one another on the shank 11 and are under tension when the brush head 20 is applied to the outlet end 22 of the nozzle. Thus, the brush B is yieldably connected to the gun A and is yieldably maintained in an operative working position relative to the nozzle during operation of the combination. This yieldable connection will also compensate for any irregularities and will maintain the parts in operative relation to each other while permitting some relative movement therebetween. In this connection it will be noted (Fig. 1) that the outlet end portion 22 of the nozzle is partially flattened and has a tapered extremity 22'.

The opening 21 in the brush head is shaped to cooperate with the tapered extremity 22' of the flattened end portion 22 to prevent relative turning movement between the brush head and nozzle and to limit upward movement of the brush relative to the nozzle, while permitting slight transverse rocking and longitudinal rocking movement of the brush relative to the nozzle. During some cleaning operations this relative movement between

the parts may be very desirable, especially as it is under the control of the yieldable tensioning means such as the coil springs 30 and 31 which maintain proper relationship between the parts.

In Figures 4 and 5, I have illustrated a slight modification wherein only one coil spring 40 is employed to attach the brush B to the gun A and to yieldably maintain the parts in proper assembled relation as aforesaid. As shown, this spring 40 is terminally connected to opposite side edges of the brush head 20 substantially midway its ends so as to form an inverted U-shaped loop for straddling the shank 11 of the nozzle 12. Otherwise the construction and operation of the parts are the same as in Figures 1 to 3 inclusive.

Regardless of the movement of the coil springs or equivalent elastic means that might be employed as attaching means for the brush, I preferably provide the shank 11 of the nozzle with an upstanding arm or hook 50 for preventing accidental displacement of the springs from said shank when the parts are in assembled relation.

Thus, from the foregoing it will be readily apparent that the brush B may be quickly attached to the gun A by simply slipping the loop or loops of the springs over the arm or hook 50 onto the shank 11 and then stretching the springs sufficiently by a downward pull on the brush B to permit insertion of the outlet end 22 of the nozzle into the opening 21 in the brush head 20. The resiliency of the spring or springs or equivalent elastic means that may be employed in the loops will then maintain the parts in proper assembled relation for use during a cleaning operation.

When it is desired to detach the brush B from the gun A, the brush is initially pulled down to free the outlet end 22 of the nozzle from the opening 21 in the brush head 20, and is then moved laterally so that the loop or loops may be removed from the shank 11 and hook 50. A different brush may then be applied to the gun, or the brush and gun may be used separately, as desired.

What I claim as my invention is:

1. A fountain brush attachment for an inverted substantially L-shaped nozzle having at one end a handle engaging shank portion and having at the other end a fluid outlet portion provided with a tapered extremity, consisting of only a brush and coil spring attaching means therefor, the brush having a head provided with an opening for detachably receiving the tapered extremity of the nozzle, the walls of said opening having correspondingly tapered portions engageable with the tapered extremity of the nozzle to limit upward movement of the brush upon the nozzle while permitting relative rocking movement between the brush and nozzle and to provide a load carrying seat for the tapered extremity of the nozzle when downward pressure is applied thereto from the handle engaging shank while the attachment is in use, and the coil spring attaching means consisting of one or more coil springs terminally connected to the head at opposite sides thereof and providing inverted substantially V-shaped loops for straddling engagement with the handle engaging shank of said nozzle, the length of said loops relative to the distance between the shank and extremity of said nozzle being such that said spring loops alone are operable to hold the head of the brush in operative position upon the tapered extremity of the nozzle, said spring loops

being yieldable while in engagement with the shank of the nozzle to permit the head of said brush to be moved by hand from the tapered extremity of the nozzle when it is desired to detach the brush from said nozzle.

5 2. A brush attachment for an inverted substantially L-shaped member having at one end a handle engaging shank portion and having at the other end an elongated portion provided with a tapered extremity, consisting of only a brush and coil spring attaching means therefor, the brush having a head provided with an opening for detachably receiving the tapered extremity of the member, the walls of said opening being engageable with the tapered extremity of the member to limit upward movement of the brush upon said member while permitting relative rocking movement between the brush and member and to provide a load carrying seat for the tapered extremity of the member when downward pressure is applied thereto from the handle engaging shank while the attachment is in use, and the coil spring attaching means consisting of one or more coil springs terminally connected to the head at opposite sides thereof and providing inverted substantially V-shaped loops for straddling engagement with the handle engaging shank of said member, the length of said loops relative to the distance between the shank and extremity of said member being such that said spring loops alone are operable to hold the head of the brush in operative position upon the tapered extremity of the member, said spring loops being yieldable while in engagement with the shank of the member to permit the head of said brush to be removed by hand from the tapered extremity of the member when it is desired to detach the brush from said member.

10 3. A fountain brush attachment for an inverted substantially L-shaped nozzle having at one end a handle engaging shank portion and having at the other end a fluid outlet portion provided with a reduced extremity, consisting of only a brush and coil spring attaching means therefor, the brush having a head provided with an opening for detachably receiving the reduced extremity of the nozzle, the walls of said opening being shaped to cooperate with said reduced extremity of the nozzle to prevent relative turning movement and to limit upward movement of the brush upon the nozzle, said walls also being shaped to provide a load carrying seat for the reduced extremity of the nozzle when downward pressure is applied thereto from the handle engaging shank while the attachment is in use, and the coil spring attaching means consisting of a single coil spring terminally connected to the head at opposite sides thereof and providing an inverted substantially V-shaped loop for straddling engagement with the handle engaging shank of said nozzle, the length of said loop relative to the distance between the shank and extremity of said nozzle being such that said spring loop alone is operable to hold the head of the brush in operative position upon the reduced extremity of the nozzle, said spring loop being yieldable while in engagement with the shank of the nozzle to permit the head of said brush to be removed by hand from the reduced extremity of the nozzle when it is desired to detach the brush from said nozzle.

CHARLES D. CLOBRIDGE.
